UNITED STATES PATENT OFFICE.

LOUIS GODDU, OF WINCHESTER, MASSACHUSETTS, ASSIGNOR TO MCKAY
METALLIC FASTENING ASSOCIATION, (GORDON MCKAY, OF CAMBRIDGE,
MASSACHUSETTS, TRUSTEE.)

NAILING-MACHINE.

SPECIFICATION forming part of Letters Patent No. 226,062, dated March 30, 1880.

Application filed January 31, 1880.

To all whom it may concern:

Be it known that I, LOUIS GODDU, of Winchester, county of Middlesex, State of Massachusetts, have invented an Improvement in 5 Nailing-Machines for Boots and Shoes, of which the following description, in connection with the accompanying drawings, is a specification.

This invention relates to nailing-machines 10 for boot and shoe work, and has special reference to mechanism for imparting to the driver-bar its quick downward motion.

The driver-bar in nailing-machines has heretofore been driven either by a spiral spring, 15 which surrounds the bar, or is inclosed in the long tube in which the driver-bar is made to reciprocate, as in numerous patents of the United States heretofore granted to me, or by a flat spring of steel or wood.

20 In this my present invention I employ a torsional spring, one end of which acts to instantly throw down the driver-actuating arm whenever the driver is released after being lifted, while the opposite end of the said 25 spring is in contact with a holding stud or stop in an adjusting-plate, whereby the force of the spring may be adjusted at will.

The employment of a short torsional spring, as herein described, enables me to make the 30 working parts more compact, cheapen their construction, and add to the durability and efficiency of the driver-actuating mechanism.

Figure 1 represents, in side elevation, a sufficient portion of a nail-driving machine to illustrate my invention; Fig. 2, a front-end elevation thereof; and Fig. 3, a sectional detail showing the hubs or supports for the torsional spring, the position of the latter being denoted in part by dotted lines.

40 In the drawings, *a* is supposed to represent part of the usual guide, in which the driver-bar is made to reciprocate, and *b* is supposed to represent the upper end of the nail-driver bar, or a bar which rises and falls in unison 45 with it.

The front end of the driver-actuating arm *c*, having its fulcrum on the stud or axle *d*, rests upon the bar *b*, and is always kept in contact therewith by the torsional spring *e*, 50 the end 3 of which bears upon the said arm or a suitable projection thereof, as in Fig. 2, while the other end, 4, of the said spring bears

against an adjustable holding stud or stop, *f*, on an adjusting-plate, *g*, having a series of holes, openings, or receivers, 5, for receiving the said stud *f* when it is desired to change the stress of the said spring *e*.

The plate *g* has a hub, *8*, to support the interior of the spring *e*, and the arm *c* has also such a hub, *c*².

In practice, the driver-bar will be lifted against the action of the spring *e* by a cam on the main or other shaft of the machine, all in the usual manner, such devices being herein omitted, as they form no part of my present 65 invention; but as soon as the driver-bar lifting-cam comes in position to permit the driver-bar to descend, the spring *e*, acting on the arm *c*, causes it to instantly descend, the force of the blow being more or less, according to the 70 adjustment of the said spring.

It is obvious, instead of moving the pin *f* in the plate *g*, that I might so connect the said plate with the stud or axle *d* as to adjust it axially upon the said axle, holding it in adjusted position by means of a set-screw or otherwise.

The end coils of spring *e* surround the hubs 8 and *c*²; but the main part of the interior of the spring, being unsupported, is left free to expand or contract by tension without loss of power or force, as would be the case if it were supported at its center by a tube or barrel extended through and filling it.

I claim—

1. In a nailing-machine, the driver-actuating arm and the torsional spring, combined with the pin or stop, and adjusting devices to control and regulate the force of the said spring and the blow of the driver, substantially as described.

2. In a nailing-machine, the combination, with the arm *c* and its hub, the short hub *8*, and spring-holder, of the torsional spring *e*, supported only at its ends, substantially as described.

In testimony whereof I have signed my name to this specification in the presence of two subscribing witnesses.

LOUIS GODDU.
